UNITED STATES PATENT OFFICE

BERNIS M. SHIPLEY, OF DAYTON, OHIO, ASSIGNOR TO THE NATIONAL CASH REGISTER COMPANY, OF DAYTON, OHIO, A CORPORATION OF MARYLAND

CASH REGISTER

Original application filed January 19, 1924, Serial No. 687,305. Divided and this application filed March 29, 1927. Serial No. 179,304.

This invention relates to cash registers and like machines and has more specific reference to special counters for such machines.

The invention is shown applied to a machine of the type illustrated and described in applications for Letters Patent of the United States, Serial Number 608,281, filed on December 21, 1922, and Serial Number 687,305, filed on January 19, 1924, by B. M. Shipley. The present application is a division of the last mentioned application.

One object of the present invention is to provide mechanism for counting the number of single item transactions of various classifications, the number of items of multiple item transactions and the number of multiple item transactions.

With this and incidental objects in view, the invention consists of certain novel features of construction and combinations of parts the essential elements of which are set forth in appended claims and a preferred form or embodiment of which is hereinafter described with reference to the drawings which accompany and form part of this specification.

Of said drawings:

Fig. 1 is a sectional view through the machine taken to the right of, and showing the transaction bank of keys, and the differential mechanism associated therewith.

Fig. 2 shows a detail view of a part of the release trip mechanism.

Fig. 3 is a side view of the transaction special counters, together with the selecting and operating mechanisms therefor.

Fig. 4 is an enlarged detail view of a part of the special counter operating and disabling mechanisms.

Fig. 5 is an enlarged detail view of one of the transaction special counters.

Fig. 6 is a side view of the right hand end of the machine in elevation, including therein a part of the operating mechanism.

Fig. 7 is a fragmentary detail view of a part of the mechanism shown in Fig. 9 in position for a single item operation.

Fig. 8 is a detail view of the total-taking lever and the part of the mechanism adjusted thereby.

Fig. 9 is a detail view a part of the transaction key locking mechanism in position for a multiple item transaction.

Fig. 10 is a plan view of the front and back totalizer lines, and shows the totalizer 55 selecting member.

General description

The machine to which the present invention is shown applied, as illustrated and described in the applications cited, consists, in general, of a plurality of manipulative keys for entering the amounts to be registered, indicating mechanism for indicating the amounts registered and the totals thereof, a 60 plurality of totalizers for accumulating the various items and transactions, and printing means controlled so as to issue receipts upon which is printed either a single item, or a plurality of items, together with the total 70 thereof. Transaction keys, clerks' keys and a total lever are provided for controlling the various elements of the machine, all of which is fully shown and clearly described in the above mentioned Shipley applications, and 75 to which reference may be had for a complete understanding of the machine.

The machine to which the present invention is shown applied is adapted for use in places of business where it is desired to register 80 transactions comprising a single item, transactions comprising a plurality of items with the total thereof, and where it is desired to count the number of single item transactions, the number of items of a multiple item trans- 85 action and the number of multiple item transactions entered into the machine.

Keyboard

The keyboard of the present machine is the 90 same as that shown and described in the above mentioned parent application Serial No. 687,305, to which reference is hereby made for a full and clear description. Only a general description of the keyboard will be given 95 herein.

The keyboard disclosed in the parent application includes four banks of amount keys, not shown herein; a bank of clerk's keys, also not shown herein, a bank of transaction keys 30 10.

and 31, (Fig. 1), a key 32 for releasing the depression transaction keys, a total lever 33 (Fig. 8), for controlling the machine on total-taking and sub-total-taking operations, and a 5 starting bar 34 (Fig. 6).

The transaction keys 30 and 31 (Fig. 1) and the transaction key release key 32 are mounted in a common frame 35 supported in the machine by cross rods 36 and 37. These 10 keys are located near the right hand side of the machine. The keys 30 are used in entering a transaction consisting of two or more items, known herein as a multiple item transaction. The keys 31 are used in entering 15 transactions comprising a single item, known herein as single item transactions.

Keys 30 and 31 are held in their normal positions by springs, not shown, and, when depressed, are held in such positions by a locking 20 detent 38, supported at its upper end by a link 39 and at its lower end by a link 40. Each of the keys 30 and 31 has a pin 41 mounted therein, which co-operates with a hook 42 on the detent 38. After a key 30 or 31 has 25 been depressed, the detent 38 is returned to its normal position by a spring 43, at which time a hook 42 embraces the pin 41 and retains the key in its depressed position.

The transaction keys 30 and 31 are not released 30 during an operation of the machine, as are the clerks' keys and amount keys. The keys 30 and 31 can be released by depressing another one of the transaction keys 30 or 31, or by depressing the transaction key release 35 key 32. This key is provided with a pin 41, which co-operates with a cam edge 44 on the detent 38 to move the detent down and release the depressed transaction key. There is no 40 hook 42 opposite the key pin 41 of the transaction key release key 32, and therefore this key will return immediately to its outward or normal position.

Transaction differential mechanism

45 Associated with the bank of transaction keys is the differential mechanism (Fig. 1) provided for adjusting the printing mechanism and indicators, selecting transaction totalizers and transaction special counters, and controlling the various elements for registering single item and multiple item transactions.

This differential mechanism consists of a 50 differentially movable arm 50 (Fig. 1), which is given a variable movement on each operation of the machine. Pinned to the shaft 51, which is the main drive shaft of the machine, is a pair of cams 52, which co-operate with two rollers 53, carried by a lever 54. The 55 lever 54 is pivoted on a differential hanger 55, supported in the machine by two rods 56. At its upper end the lever 54 is connected by means of a link 57 to a segment 58, pivotally 60 mounted on a stud 49, carried by the hanger 55. The cams 52 receive one clockwise rota- 65

tion on each operation of the machine, which, through the mechanism just described, rocks the segment 58 first clockwise and then counter-clockwise, to its normal position. The segment 58 receives this invariable excursion 70 on each operation of the machine. The arm 50 is connected to the segment 58 by a latch 59, the foot of which engages a shoulder on the segment 58, and is held in this position by a spring 60. The latch 59 is supported on 75 the arm 50 by a link 61 and a bell crank 62. As the segment 58 is moved up, the arm 50 is carried with it until an end 63 of the bell crank 62 contacts the end of the depressed key, whereupon the bell crank is rocked counter-clockwise, to withdraw the foot of the latch 59 from the shoulder on the segment 58, and enter a nose 64 on the latch, in the proper notch 65 in a plate 66, supported by one of the rods 56 and the upper end of the hanger 55. 80 The segment 58 continues its regular excursion and on its return movement, as the shoulder thereon arrives opposite the foot of the latch, the spring 60 withdraws the nose 64 from the plate 66 and reengage the latch 59 with the segment 58. At this time a stud 67 85 on the arm 50 is contacted by a surface 68 on the segment 58 which returns the arm 50 to its normal position.

Transaction key locking mechanism

It is desired to lock the depressed transaction keys 30 and 31 (Fig. 1) against release during the registration of the items of a multiple item transaction and until the total 100 thereof has been taken. For this reason a locking mechanism is provided, under the control of the total-taking lever 33 (Fig. 8). This locking mechanism will now be described.

A releasing bar 70, (Figs. 1, 2, 7 and 9) swung at its upper end on a link 71 and at its lower end on a link 72, is provided for the purpose of adjusting an interlock to permit the machine to be released as will hereinafter be described. The bar 70 also controls the transaction key locking mechanism. The link 72, which supports the bar 70 at its lower end has a notch 73 formed in its periphery, and adapted to co-operate therewith 110 is a yoke 74, adjacent to, and fastened to, a spring pulled arm 75 loosely mounted on a shaft 76, and retained in its normal position by a stud 77, carried by the differentially movable arm 50.

By referring to Fig. 9 it can be seen that when a key 30, (Fig. 1) which keys are used in registering multiple item transactions, is depressed, the bar 70 is cammed to the left and down by the pin 41 on the key engaging an inclined edge 78 of the bar. This movement of the bar 70 rocks the link 72 about its pivot a distance sufficient to bring the notch 73 opposite the yoke 74.

It will be recalled that shortly after the 115

beginning of the operation, the arm 50 is moved up, or clockwise about its pivot. This movement of the arm removes the pin 77 from the path of the arm 75 whereupon a 5 spring 79 causes the arm 75 to rock counter-clockwise, which positions the yoke 74 in the notch 73. Then as the arm 50 returns to its normal position, as described above, the stud 77 passes to the right of the arm 75, as 10 shown in Fig. 9.

With the arm 75 in this position, it can be seen from Fig. 9 that the yoke 74 is in the path of the link 40, supporting the locking 15 detent 38 at its lower end. This prevents the downward movement of the link 40 and locks the detent 38 against movement, thus preventing release of the depressed key until the arm 75 is moved to restore the yoke 74 to its normal position, free of the notch 73. 20 This is accomplished by adjusting the total lever 33 (Fig. 8) in a manner which will now be described.

After the last item of a multiple item transaction has been entered, the machine is 25 prepared for taking the total thereof, by moving the total lever from its add position to its item total position, which is a counterclockwise movement, as viewed in Fig. 8. The lever 33 is provided with a slot 80 30 for giving an initial clockwise movement to the shaft 76, prior to a total-taking operation. Projecting into this slot is a pin 81, carried on a lever 82, pivoted at 83. An arm 84 also pivoted at 83, is held in coactive relation with an upwardly extending arm 85 on the lever 82 by a spring 86 stretched between them. The arms 84 and 85 are shaped to 35 form a cam slot 87 into which projects a pin 88 carried by an arm 89, pinned to the shaft 76.

The counter-clockwise movement of the lever 33 rocks the lever 82 and consequently the arms 84 and 85 counterclockwise, which, 40 through the slot 87 and pin 88 rocks the arm 89 and shaft 76 slightly clockwise. This movement of the shaft 76 rocks an arm 90 (Figs. 1, 7 and 9), pinned thereto, into contact with a stud 91 on the arm 75, as shown 45 in Fig. 9. The arm 90 is adapted to be moved farther during total taking operations to 50 co-operate with the stud 91 to rock said arm clockwise against the tension of the spring 79.

It will be recalled that the arm 90 is moved 55 to the position just described before the machine is released for a total-taking operation. Just before the second cycle of a total-taking operation the shaft 76 receives an additional clockwise movement by mechanism herein-after to be described. This second movement of the shaft 76 takes place with the arm 90 in contact with the stud 91, and therefore the arm 75 is rocked clockwise about its pivot, which removes the yoke 74 from the path of the stud 77. As the arm 50

returns to its home position near the end of a total-taking operation the stud 77 mounted thereon contacts the left side of the arm 75 to restore it to its normal position.

The shaft 76 is given its second clockwise movement by a cam groove 92 (Fig. 6), adapted to co-operate with a roller 93, carried on a pitman 94. The roller 93 is normally held in a notch in the groove 92, and withdrawn from its effective position in the groove by the total lever, in a manner well known in the art. For a detailed description of the mechanism for withdrawing the roller 93 from the notch see Letters Patent of the United States, No. 1,242,170, granted to F. L. Fuller on October 9, 1917. The pitman 94 is guided by a stud 106 upon which the cam 92 is freely mounted. At its left hand end the pitman is pivoted to one end of the lever 107, pivoted on a stud supported by the side frame of the machine. At its opposite end the lever 107 is connected by a link 108 to an arm 109, pinned to the shaft 76. The cam 92 receives one counter-clockwise rotation on a total-taking operation in a manner later to be described, and which through the mechanism just described, gives the shaft 76 its second clockwise movement.

Mechanism is provided which is associated with the transaction differential for adjusting the selecting means for the special counters appropriate to the transaction key depressed. This mechanism includes a beam 95 (Fig. 1) pivotally mounted on the arm 50, and at its right hand end bifurcated to co-operate with a pin 96 mounted in a link 97. At its lower end the link is pivoted to an arm 98 secured to one end of the sleeve surrounding a shaft 99, carried by the side frames of the machine. At its upper end the link 97 is pivoted to an aligner segment 100, pinned to a shaft 101. A roller 102 is mounted on the lever 54 to co-operate with the beam 95 to position the beam commensurate with the transaction key 30 or 31 depressed.

Co-operating with the aligning notches in the segment 100 is an aligner 103, carried by a plurality of arms 104, pinned on a shaft 105. The aligner 103 is adapted to be disengaged from the segment 100 to permit the segment to be adjusted. The mechanism for operating the aligner is neither shown nor described herein, as it forms no part of this invention and is fully shown and clearly described in applicant's above mentioned co-pending application, Serial Number 608,281, filed December 21, 1922 to which reference may be had for a complete understanding thereof.

Transaction special counters

The machine is provided with nine transaction special counters (Fig. 3), one for each of the keys 30 and 31, and two for counting

the number of cash and charge multiple item transactions. These special counters are of the same type as those shown and described in Patent No. 1,394,256, issued to Fuller, October 18, 1921.

6 The counters are the usual step-by-step type and are supported on shafts 110 mounted in a frame 111 supported in the machine near its left hand end by the rods 36 and 37. The 10 wheels 112 (Fig. 5) of the counters are moved step-by-step by the usual tined carrying pawls 113, which co-operate with the ratchets 114 secured to the counter wheels 112. Each pawl 113 is pivoted on a yoke 115, 15 pivoted on shaft 110 and held in engagement with the ratchet 114 by a coil spring 116. Pivoted to the yoke 115 is a link 117 which at its opposite end carries a stud 118, to which is pivoted another link 119. The link 119 is 20 slotted to surround a stud 120 mounted in the frame 111. An operating bar 121 (Figs. 3 and 5), supported at its upper end by an arm 122 and at its lower end by an arm 123, is provided with a plurality of slots 124, one to 25 co-operate with each of the studs 118. The bar 121 is given a movement to the left and down, on each operation of the machine by mechanism presently to be described. It can be clearly seen from Fig. 5 that if an obstruction 30 is placed opposite the lower end of the link 119 the downward movement of the bar 121 will, through the slot 124 and stud 118, cause the link 119 to rock counter-clockwise about the stud 120 and to move the link 117 35 to the left whereby the link 117 will rock the yoke 115 and the tined pawl 113 clockwise to advance its associated counter one step. As the bar 121 moves up, the parts co-operating therewith will be restored to their normal 40 positions.

Obviously if no obstruction is in position opposite the end of the link 119 (Figs. 3 and 5), this link will be slid idly in the direction of its length over the stud 120 and at the same 45 time the stud 118 will be moved toward the bottom of the slot 124, thereby rocking the link 117 idly about its pivot on the yoke 115.

The mechanism mentioned above, for actuating the bar 121 will now be described.

50 An arm 135 (Figs. 3 and 4) pivoted on one of the rods 56 is bifurcated at its upper end to cooperate with a pin 125 carried by a downwardly extending finger of the arm 123. Pivoted to the arm 135 is a link 126 carrying 55 at its opposite end a pin 127, projecting into a right angle opening 128 formed in an arm 129, pinned to a shaft 130. This shaft is given a rocking movement first counter-clockwise and then clockwise to its normal position 60 by a cam groove 131 (Fig. 6), cut in the side of a gear 134, pinned to the main drive shaft 51. Pinned to the right hand end of the shaft 130 is an arm 132, to which is pivoted one end 65 of a pitman 133. The pitman 133 at its right hand end carries a roller projecting into the

cam groove 131. It will be remembered that the shaft 51 is given one clockwise rotation on each adding operation of the register. The cam groove 131 is shaped so as to give the shaft 130 the rocking movement described above. This counter-clockwise movement of the shaft through the arm 129 and link 126 rocks the arm 135 counter-clockwise, which in turn rocks the arm 123 supporting the operating bar 121, clockwise, and gives to the bar 121 its reciprocating movement to actuate the special counters.

Selecting the transaction special counters

The counters 140 and 141, (Fig. 3) are 80 actuated to count the the number of items of multiple item transactions for the item charge and item cash keys respectively. The counters 142 and 143 are for counting the number of multiple item transactions for these keys. 85 The counters 144 are used for counting the number of single items registered and are selected by the keys 31.

As previously stated, to operate a special counter, it is necessary to place an obstruction 90 opposite the end of the link 119 peculiar to the counter upon which it is desired to add one. This obstruction comprises a stop 145 (Fig. 3) slidably mounted on a lever 146 and spring-urged toward the stud 147 upon which the lever 146 is loosely mounted. The stop 145 is guided by studs 148 and 149, mounted on the lever 146, and held normally in its effective position by means of a segmental cam plate 150, pivoted on the stud 147, and the 100 periphery of which is always contacted by the inner end of the stop 145 said stop being held in contact with the periphery of the segmental plate by the spring 165.

The stop 145 is moved to select the transaction counters commensurate with the transaction keys depressed, by the differential mechanism associated with the transaction bank (Fig. 1).

It will be recalled that the link 97, segment 110 100 and shaft 101 are differentially positioned according to the transaction keys depressed. Pinned to the shaft 101, near its left hand end is an arm 151, (Fig. 3), connected to the lower end of the lever 146 by 115 a link 152. Clearly, as the beam 95 (Fig. 1) is adjusted to its various positions, depending upon which one of the transaction keys is depressed, the link 97, segment 100, shaft 101, arm 151, (Fig. 3), and the lever 146, will be correspondingly positioned, and will remain so positioned until another key is depressed and the machine operated, whereupon the parts just enumerated will be moved to their new positions. The transaction differential mechanism (Fig. 1) is shown in its zero or home position, to which it returns at the end of each operation. The differentially adjustable lever 146 is shown in Fig. 3 in the position to which it is adjusted under the influ- 120 125 130 135 140 145 150 155 160 165 170 175 180 185 190 195 200 205 210 215 220 ence of the upper one of the keys 30, that is, the item charge position.

With the stop 145 in the position shown in Fig. 3, the movement of the operating bar 121 to the left will cause the toggle formed by the links 119 and 117 to be straightened, which through the yoke 115 and tined pawl 113, will cause the counter wheel to advance one step. The toggles associated with the remaining eight counters will be ineffective, as previously described, the links 119 sliding idly over the studs 120, and the studs 118 sliding idly toward the bottom of the slots 124 in the bar 121.

15 The counters 140 and 141 and the single item counters 144 are selected for operation by stop 145 in the manner just described. The counters 142 and 143, which count the number of multiple item transactions, are selected in a slightly different manner. It will be recalled that after the last item of a multiple item transaction has been entered, the machine is prepared for a total-taking operation by moving the total lever 33 (Fig. 8) 20 from its add position to its item total position, which movement, as previously described, will rock the shaft 76 slightly clockwise.

25 A bell crank 155 (Fig. 3) pinned to the shaft 76 near its left hand end is connected by a link 157 to an arm 156, pivoted on the stud 147. The arm 156 is rigidly connected to the cam plate 150 by a hub. The clockwise movement of the shaft 76 will, through the bell crank 155 and the link 157, rock the arm 30 156 and cam plate 150 counterclockwise. As previously mentioned, near the end of the first cycle of the total-taking operation, the shaft 76 is given a second clockwise movement in a manner previously described. This second movement of the shaft 76 will cause an angle edge 158 of the arm 156 to engage a pin 159, mounted in an arm 160 and rock this arm clockwise to move a lip 161, to its effective position opposite the link 119 for the counter 142. As the operating bar 121 is moved, the end of the link 119 associated with the "charge total" counter, contacts the lip 161, and as the bar 121 continues its movement, the link 117 is moved forwardly to rock the 35 yoke 115, whereby the pawl 113 advances the counter one step. As the cam plate 150 is rocked counter-clockwise, the stop 145 influenced by a spring 165 stretched between a stud on the stop 145 and the stud 149 in the 40 lever 146 will move from the high section 162 of the cam plate 150 to the low section 163 thereof, in which position the stop is ineffective and cannot operate the counters 140. The pin 159 normally rests on a projection of the lever 146, being held in this position by a spring 164.

45 The operation of the counter 143, which counts the number of multiple item cash transactions, is similar to that of the counter 142, just described. The only difference is

that the lever 146 is moved one position counter-clockwise by the differential mechanism, to place the arm 160 in its proper position, relative to the link 119 of the counter 143.

Special counter disabling mechanism

Mechanism is provided by means of which the special counter operating mechanism will be disabled on the first cycle of a multiple item total-taking operation.

It will be remembered that when the total lever 33, (Fig. 8) is moved to prepare the machine for a total-taking operation, the shaft 76 is given an initial movement in a clockwise direction. Loosely mounted on the shaft 130 is a three-armed lever 170, (Fig 3), which on its upwardly extending arm carries a pin 171 projecting into the cam slot 172 formed in one arm of the bell crank 155. As the bell crank 155 is pinned to the shaft 76, the slot 172 by acting on the pin 171, will rock the lever 170 counter-clockwise. The lever 170 has a downwardly extending foot 173 contacting a pin 174 mounted in a lever 175 (Figs. 3 and 4). At its opposite end the lever 175 carries a pin 176 projecting into a slot in the link 126. The clockwise movement of the lever 170 will, through the pin 174, rock the lever 175 counter-clockwise, which in turn will cause the link 126 to rock clockwise about its pivot on the arm 135 (Fig. 4) a distance sufficient to place the pin 177 in an ineffective position in the opening 128. Just before the beginning of the second cycle of a total-taking operation the shaft 76 is given a second clockwise movement. The cam slot 172 in the bell crank 155 is shaped so that a second clockwise movement thereof will move the pin 171 and the lever 170 clockwise to their normal positions. A spring 177 stretched between one arm of the member 170 and the lower end of the lever 175, will rock this lever clockwise to its normal position which, through the pin 176, will move the link 126 counter-clockwise and reengage the pin 177 with a notch in the opening 128, thus effecting an operative connection to operate the special counter on the second cycle of an item total-taking operation.

The transaction special counter operating mechanism is rendered ineffective when reading or resetting the single item totalizers selected under control of the keys 31 (Fig. 1), as it is not desirable to advance the special counters 144 associated therewith on total-taking operations.

To accomplish this, an arm 180 (Figs. 4 and 8) pinned to the shaft 99 near its left hand end, is constantly urged counter-clockwise by a spring 181. The arm 180 is held in its normal position by a roller 182 (Fig. 8) carried on a lever 183 pivoted on one of the rods 56, and engaging a block 184, riveted on the lever 33. The lever 183 is bifurcated at its

lower end to engage a pin 185 carried by an arm 186, pinned to the shaft 99. When the lever 33 is moved two steps counter-clockwise to prepare the machine for resetting the 5 single item totalizers, an inclined edge 187 of the block 184 is brought opposite the roller 182 whereupon the arm 180, is rocked counter-clockwise under the influence of the spring 181, until arrested by a stud 188 projecting from the side frame of the machine. The counter-clockwise movement of the arm 180 will through its engagement with a pin 189 carried by a lever 190, rock the lever 190 counter-clockwise. The downwardly extending 15 arm of the lever 190 engages a pin 192 mounted on the lever 175, previously described, and rocks this lever counter-clockwise, which in turn rocks the link 126 clockwise to remove the pin 127 from its effective 20 position to its ineffective position in the opening 128 in the arm 129. The operating bar 121 will not be affected by the movement of the arm 129 when the pin 127 is in such ineffective position.

25

Totalizers

The machine illustrated has nine totalizers (Figs. 1 and 10), arranged on three lines. The upper line contains but one totalizer, 30 used for accumulating the total of the "multiple item" transactions. This totalizer is controlled by the "multiple item" keys 30, so that during any operation of the machine with a key 30 depressed, this upper totalizer 35 is brought into mesh with the actuators to have the amounts added thereto. A total is printed of all the items of a "multiple item" transaction entered into this totalizer, and therefore, this upper totalizer is rocked into 40 engagement with the actuators to control the adjustment of the printing elements, as described in the parent application, and the totalizer is simultaneously turned to zero, as is well known in the art. Thus, after each 45 complete entry of a "multiple item" transaction, and the total printing thereof, the upper totalizer is turned to zero, so that this totalizer will be ready for the next "multiple item" transaction.

50 Depression of a "single item" key 31, controls the totalizer engaging mechanism for the upper totalizer so that it is not engaged with the actuators during the operation of the machine, and therefore, the amounts of 55 the "single item" transactions are not entered into the upper totalizer.

The front totalizer line has four totalizers (Fig. 10), used to accumulate totals for an extended period of time, for example, 60 "weekly totals". There is one totalizer on this line for each class of transaction represented by the transaction keys 30 and 31, namely, "cash", "charge", "received-on-account", and "paid out".

65 The back totalizer line also has four total-

izers thereon, one for each classification, the same as the front line, and may be used as "daily totals".

Both the front and back totalizer lines are shifted under control of the transaction keys 70 30 and 31 to bring the proper totalizers into alignment with the actuators, as will be later more fully described. Both the "multiple item" cash key 30 and the "single item" cash key 31, control the front and back totalizer 75 lines to align the "cash daily totalizer" and "cash weekly totalizer" with the actuators, so that if either one of these two keys is depressed, and the machine operated, the amount of the items set up on the keyboard 80 is added into the "cash weekly" totalizer on the front line and the "cash daily" totalizer on the back totalizer line. The "charge" totalizers are selected by both the "multiple item" charge key 30, and the "single item" 85 charge key 31. The "Paid out" key 31 and the "Received-on-account" key 31 each selects its appropriate totalizer. Thus depression of any of the transaction keys will select the appropriate totalizer on each of the front and 90 back totalizer lines.

The mechanism for meshing the selected totalizer on the front and back totalizer lines with the actuator, is controlled so that the 95 two totalizers will be moved into mesh with the actuators during every item entering operation, in order that every item entered into the machine will be entered into the appropriate totalizers. However, when taking totals, any one of the totalizer lines can be 100 selected by moving the total control lever 33 to the proper position.

Each of the above totalizers includes 105 pinions 199 (Fig. 10). These totalizers are the same type as illustrated in the patent to W. A. Chryst, No. 1,230,864, dated June 26, 1917, and the patents to F. L. Fuller, No. 1,242,170, dated October 9, 1917, and No. 1,394,256, dated October 18, 1921. The totalizer carrying frames are illustrated in Fig. 1. 110 As the frames are practically the same as those illustrated and described in the Fuller patents 1,242,170 and 1,394,256, only a brief description will be given herein. Each set of totalizer pinions 199 (Fig. 10) is loose on a tube 198, carried by frames 200, 201 and 202, respectively, mounted on opposite ends of the tube and slidably mounted on shafts 203, 204 and 205, respectively. The inner ends of the frames 200, 201 and 202 are slotted 115 to engage blocks 197 (Fig. 10) secured to the hangers 55 to prevent the frames from turning on the shafts 203, 204 and 205. The tubes 198, together with their respective frames 200, 201, or 202, form unitary structures 120 slidably on the shafts 203, 204 or 205, for laterally positioning the pinions 199 into cooperative relation with the differential segments, as is old and well known in the art and described 125 in the Fuller patents above referred to. 130

The front and back totalizer lines, each with their four totalizers are moved laterally by the differential mechanism (Fig. 1) under the control of the transaction keys 30 and 31. The mechanism for laterally shifting the totalizer lines under control of the transaction keys is as follows:

Connected to the arm 98 (Fig. 1), which it will be remembered is differentially positioned under control of the keys 30 and 31, is a segment gear 206, meshing with a rack 207 secured to a bar 208. The bar 208 is slidably mounted on two studs 209, and has a flange 210 at each end. Formed in the flanges 15 are cam slots 212 (Fig. 10) into which project rollers 213 carried by slides 211. These slides co-operate with projections on the totalizer frames 200 and 201, to slide these frames laterally in the machine for the purpose of selecting totalizers, all of which is fully shown and described in the previously mentioned applications.

The cam slots 212 are duplicates and are so formed that the front and back totalizer lines move like extents simultaneously, so that corresponding totalizers are selected on the two lines. The cam slots 212 are also formed to select the same totalizer on each line when either the cash "single item" key 31, or the cash "multiple item" key 30, is depressed. The "charge" single item key 31, or the "charge" multiple item key 30, when depressed, selects the same totalizer on each line. The release key 32 never selects a totalizer 35 since this key is never held depressed while the machine is operated. There is no totalizer corresponding to the "No sale" key, and therefore, there are six keys in the transaction bank for selecting totalizers, and only four totalizers on each line to be selected, the "cash" and "charge" totalizers each being selected by two keys and duplicate totalizers, one on each line, are selected during each operation of the machine.

45 *Operating mechanism*

The machine as shown is operated manually by a crank 215, which has integral therewith a gear 216 meshing with gear 217, which 50 in turn meshes with the gear 134 pinned to the main drive shaft 51, previously described. The ratio of the gears is such that two clockwise rotations of the crank 215 will give one-half of one counter-clockwise rotation of the gear 217 and one clockwise rotation to the gear 134 and the main drive shaft 51 on each adding operation of the machine. It is to be understood that during total taking operations the shaft 51 is given two complete rotations, thus requiring four rotations of the gear 216.

The machine may also be driven by a motor which is not shown or described herein, as 65 it forms no part of the invention.

Machine release

The machine is released for operation by depressing a clerk's key (not shown) a transaction key 30 or 31 (Fig. 1) and a starting bar 34 (Fig. 6). This permits the shaft 220 to be rocked clockwise to release the machine for operation in a manner fully illustrated and described in the previously mentioned application Serial No. 687,305.

The shaft 220 normally tends to rock clockwise under the influence of a spring 221 compressed between the bottom of a slot in a link 222 and the shoulders of two identical spring clips 223, pivoted on an arm 224, pinned to the shaft 220. Also pinned to the shaft 220 is an arm 225 which carries a flattened stud 226. A pawl 227 pivoted on a stud mounted in the side frame 228 of the machine normally lies in the path of the stud 226, thereby holding the shaft 220 in its normal position. Depressing the starting bar 34 will, through a stud on a slide 229 engaging a bifurcated portion of an arm 230 connected by a link 231 to a downwardly extending arm 232 of the pawl 227, rock the pawl counter-clockwise out of the path of the flattened stud 226 whereupon the spring 221 will expand and rock the shaft clockwise to release the machine.

An interlock between the starting bar 34 (Fig. 6) and the transaction keys 30 and 31 (Fig. 1) is provided whereby it is necessary to depress a transaction key 30 or 31 before the machine can be released for operation by depressing the starting bar 34.

Pinned to the shaft 220 (Fig. 2) is an arm 235, upon which is mounted a flattened stud 236. A projection on an interlocking pawl 237 pivoted on a shaft 238 normally lies in the path of the stud 236. The interlocking pawl 237 is held in contact with a yoke 239 by a spring 240. The yoke 239 has an upwardly extending arm 241, held in engagement with a pin 242 carried on the arm 71, supporting the release bar 70 at its upper end. The movement of the bar 70 toward the left as the transaction key 30 or 31 is depressed, will rock the arm 71 clockwise, which through the pin 242 and the arm 241 will rock the yoke 239 and interlocking pawl 237 counter-clockwise to remove the projection on the interlocking pawl 237 from the path of the stud 236 whereupon the shaft 220 is free to be released by depressing the starting bar 34.

Near the end of each operation it is necessary to restore the shaft 220 to its normal position and also to restore the release pawl 227 to its normal position in the path of the flattened stud 226, and to restore the projection on the interlocking pawl 237 to its normal position in the path of the stud 236.

The mechanism for restoring these parts, just enumerated, to their respective normal positions is best shown in Fig. 6, and includes a cam groove 245 cut in the face of the gear 130

217 and into which projects a roller 246 carried by an arm 247 pivoted on a stud supported by the side frame 228 of the machine. At its right hand end the arm 247 carries a pin 248 engaging a notch in an opening 249 in the link 222, previously mentioned. The cam groove 245 is shaped to rock the arm 247 clockwise and back to its normal position near the end of each operation of the machine. It will be recalled that at the beginning of the operation, the arm 224 is rocked clockwise by the spring 221, which positions the stud carried by this arm in the top of the slot in the link 222. The clockwise movement of the arm 247, as just described, will through the pin 248, link 222 and arm 224, rock the shaft 220 counter-clockwise slightly past normal, whereupon the starting bar 34, pulled by spring 244, will return to its normal position, which through mechanism hereinbefore described will restore the release pawl 227 to its position in the path of the stud 226. The shaft 220 then rocks clockwise until the stud 226 rests against the pawl, in which positions the parts are ready to be released for another operation. The interlocking pawl 237 is similarly restored to its normal position.

On the total-taking operation the machine receives two complete operations or cycles of operation, and it is necessary to prevent restoration of the parts just described to their normal positions near the end of the first cycle of operation, and mechanism provided therefor will now be described.

Referring to Figs. 6 and 8, it will be remembered that the shaft 76 is given a preliminary clockwise movement when the total lever 33 is moved to prepare the machine for a total-taking operation. This movement of the shaft 76 through arm 109 (Fig. 6) link 108 and lever 107, moves the pitman 94 to the left a distance sufficient to remove the roller 93 thereon from the notch in which it normally rests, into effective relation with the cam groove 92. This initial movement of the pitman also moves a coupling plate 250 to couple the cam 92 to the gear 217 in such a manner that they will be rotated in unison. Further description of the coupling plate 250 is not thought necessary, as it is old and well known in the art and shown and described in detail in the aforesaid Fuller patent, No. 1,242,170. At its right hand end the pitman 94 is provided with a stud 251 co-operating with a slot 252 formed in the lower end of the link 222. During the first cycle of operation of the total-taking operation, the cam 92 will give the pitman an additional movement to the left which by means of the stud 251 will rock the link 222 clockwise and position the opening 249 therein so as to render the pin 248 ineffective on its downward movement. During the second cycle the plate 222 is restored and the shaft 220 will be restored as described above.

While the forms of mechanisms herein shown and described are admirably adapted to fulfill the object primarily stated, it is to be understood that it is not intended to confine the invention to the forms or embodiment herein disclosed, for it is susceptible of embodiment in various forms all coming within the scope of the claims which follow.

What is claimed is:—

1. In a machine capable of accumulating items, an item counter, actuating means therefor, an arm positioned during an accumulating operation to select the counter for actuation, a retractable member carried by said arm adapted in its projected position to render said actuating means effective, and adjustable means for holding said member in projected position. 75

2. In a machine capable of accumulating items, an item counter, actuating means therefor, an arm positioned during an accumulating operation to select the counter for actuation, a movable member carried by said arm adapted in one position to render said actuating means effective and in another position to render it ineffective, and adjustable means for holding said member in effective position. 85

3. In a machine capable of accumulating items, an item counter, actuating means therefor, an arm positioned during an accumulating operation to select the counter for actuation, a movable member carried by said arm adapted in one position to render said actuating means effective and in another position to render it ineffective, and a cam for holding said member in effective position. 95

4. In a machine capable of accumulating items, an item counter, actuating means therefor, an arm positioned during an accumulating operation to select the counter for actuation, a movable member carried by said arm adapted in one position to render said actuating means effective and in another position to render it ineffective, adjustable means for controlling the movable member relative to its effective and ineffective positions, and means for moving said member into ineffective position when said adjustable means is in one of its positions of adjustment. 100

5. In a machine capable of accumulating items, an item counter, actuating means therefor, an arm positioned during an accumulating operation to select the counter for actuation, a movable member carried by said arm adapted in one position to render said actuating means effective and in another position to render it ineffective, and a pivoted member for controlling the movement of said member into ineffective position. 110

6. In a machine capable of accumulating items, an item counter, actuating means therefor, an arm positioned during an accumulating operation to select the counter for actuation, a spring actuated retractable 115

120

125

130

- member carried by said arm and adapted in its projected position to render said actuating means effective and means to control said member so that the latter will move into an ineffective position. 5
7. In a machine capable of accumulating items, an item counter, actuating means therefor, an arm positioned during an accumulating operation to select the counter for 10 actuation, a spring actuated retractable member carried by said arm and adapted in its projected position to render said actuating means effective, and a member having high and low portions respectively to hold the retractable member in effective position and to control said retractable member so that the latter can move into an ineffective position. 15
8. In a machine capable of accumulating items, an item counter, actuating means therefor, a differentially settable means, a 20 movable element mounted on the settable means adapted to be positioned to render said actuating means effective and ineffective, and a cam for controlling the position of said 25 movable element.
9. In a machine of the class described, an item counter, actuating means therefor, means adapted to be positioned to render said actuating means effective and ineffective, a 30 total control means, and a movable member for holding said positioned means in effective position and adapted under control of said control means to move into ineffective position. 35
10. In a machine capable of two cycle operations, a counter actuating means, driving means therefor operable during each cycle of operation, means for disconnecting the driving means from the actuating means during 40 the first cycle of each two-cycle operation and for connecting them during the second cycle, and means for preventing the connection from being effected during the second of certain two-cycle operations. 45
11. In a machine capable of two-cycle operations, a counter actuating means, driving means therefor operable during each cycle of operation, means for disconnecting the driving means from the actuating means, and 50 means to determine the effectivity of the disconnecting means during the second cycle of operation. 55
12. In a machine capable of two-cycle operations, a counter actuating means, driving means therefor operable during each cycle of operation, manipulative means for preparing the machine for two-cycle operations and for disconnecting the driving means from the actuating means, and means controlled by said 60 manipulative means for causing said parts to remain disconnected or to be connected during the second cycle of operation. 65
13. In a machine capable of two-cycle operations, a counter actuating means, driving means therefor operable during each cycle of 70 operation, manipulative means for preparing the machine for two-cycle operations, a cam operated by said manipulative means for disconnecting said driving means from said actuating means, and means for operating said cam during operations of the machine for causing said parts to be connected for actuating during the second cycle. 75
14. In a machine capable of two-cycle operations, a counter actuating means, driving means therefor operable during each cycle of operation, manipulative means for preparing the machine for two-cycle operations, a cam operated by said manipulative means for disconnecting said driving means from said actuating means, means for operating said cam during operations of the machine for causing said parts to be connected for actuation during the second cycle, and means for counter- 80 acting the effect of said second movement of the cam during certain two-cycle operations. 85
15. In a machine capable of registering multiple item transactions of different classifications, an item counter for counting the number of items in each class, a counter for 90 counting the number of transactions in each class, common operating means for said counters, and a manipulative means for controlling the machine for item and total operations and selecting the appropriate counter for operation. 95
16. The combination of a plurality of sets of counters, a differentially movable arm for selecting a set of counters, means carried by said arm for causing an operation of any 100 one of the counters of the set selected, and a lever for controlling said last mentioned means to selectively operate the counter of the set selected. 105
17. The combination of a plurality of sets of counters, a differentially movable arm for selecting a set of counters, means carried by said arm for causing an operation of any 110 one of the counters of the set selected, and cam means for controlling said last mentioned means to selectively operate the counter of the set selected. 115
18. The combination of a plurality of sets of counters, means adapted to be positioned to select any one of said sets for operation, means carried by said positioned means for causing counters of the set selected to operate, and means for causing said last mentioned means to operate any one of the counters of the set selected. 120
19. The combination of a plurality of sets of counters, means adapted to be positioned to select any one of said sets for operation, a plurality of movable means carried by said selecting means, one for each counter of a 125 set of counters, for causing operation of said counters, and means for controlling the effectivity of said movable means. 130
20. The combination of a plurality of sets of counters, means for selecting any one of

- said sets of counters, a slidable member carried by said selecting means for causing an operation of one of said counters, a pivoted member carried by said selecting means for 5 causing an operation of another counter, and means for moving said members into effective or ineffective positions.
21. The combination of a plurality of sets of counters, movable means for selecting any 10 one of said sets, and add and total operation control means, a slidable member carried by said selecting means for causing one counter of the set selected to operate during adding, a pivoted member carried by said 15 selecting means for causing another counter to function during total operations, and means controlled by said operation control means for moving said slidable and pivoted members alternately into effective and ineffective positions.
22. The combination of two sets of counters, each set comprising two counters, a pivoted arm for selecting either set, two movable members carried by said arm for 25 causing said counters to be operated, and two cam members rigidly connected together for movement in unison and adapted to alternately project said movable members and control their withdrawal.
23. The combination of two sets of counters, each set comprising two counters, a pivoted arm for selecting either set, two spring-actuated retractable members carried 30 by said arm for causing said counters to be operated, two cam members rigidly connected together for movement in unison and adapted to project either member and control the withdrawal of the other, and add and total control means for controlling the movement of said cam members.
24. The combination of two sets of counters, each set comprising two counters, movable means adapted to be positioned in operative relation with respect to either set, 45 a plurality of movable members carried by said movable means for causing said counters to operate, and cams for causing said movable members to move into and out of effective positions.
- 50 25. The combination of two sets of counters, each set comprising two counters, movable means adapted to be positioned in operative relation with respect to either set, a plurality of movable members carried by 55 said movable means for causing said counters to operate, and oppositely facing cams for causing said movable members to move into and out of effective positions.
- 60 26. The combination of a plurality of sets of counters, each set comprising a plurality of counters, means movable into position to select any set, a plurality of retractable elements carried by said selecting means for severally causing operation of said counters, 65 and means for controlling the effectivity of said retractable elements in either position of said selecting means.
27. The combination of two sets of counters, each set comprising an item counter and a total of items counter, means adapted to be positioned to select either set of counters, movable elements carried by said means for causing said counters to be operated, and means controlled during item and totaling operations to select the appropriate counter in either position of said selecting means.
- 70 28. In a machine capable of one- and two-cycle operations, the combination of two sets of counters, each set comprising two counters, means for selecting either set, means carried by the selecting means and operable in either position of said selecting means for causing an operation of the appropriate counter during one-cycle operations, and other means carried by the selecting means and operable in either position of said selecting means for causing an operation of the other counter during two-cycle operations.
- 75 29. In a machine capable of one- and two-cycle operations, the combination of two sets of counters, each set comprising two counters, means for selecting either set, means carried by the selecting means and operable in either position of said selecting means for causing an operation of the appropriate counter during one-cycle operations, other means carried by the selecting means and operable in either position of said selecting means for causing an operation of the other counter during two-cycle operations, and cams for controlling the effectivity of said means causing operation of said counters.
- 80 30. The combination of a plurality of counters, a differentially movable arm for selecting one of said counters, a retractable means carried by said arm for causing an operation of the selected counter, means for maintaining said retractable member in projected position, and total control means for causing said retractable member to move to ineffective position.
- 85 31. The combination of single counters and pairs of counters, a differentially movable arm common to all counters for selecting one of the single counters and one of the pairs of counters, means carried by said arm for causing an operation of a selected single counter or one counter of a selected pair of counters, other means connected to the differentially movable arm for causing an operation of the other counter of a pair selected, and manipulative means for determining which of the first two mentioned means will cause a selected counter of a pair of counters to be operated.
- 90 32. In a machine capable of accumulating single item transactions and items of different classes of multiple item transactions and taking totals thereof, single counters appropriate to said single item transactions, pairs 95
- 100
- 105
- 110
- 115
- 120
- 125
- 130

- of counters appropriate to the different classes of multiple item transactions, each pair comprising an item counter and a total counter, a differentially movable means common to all 5 counters for selecting one of the single counters or one of the pairs of counters for operation, manipulative means for controlling the movement of said differentially movable means, means carried by the differentially 10 movable means for causing an operation of the counter selected from the single counters or one counter from the pairs of multiple-item counter during accumulating operations, other means carried by said differentially 15 movable means for causing an operation of the total counter of a selected pair of counters during total taking operations, and an add and total control manipulative lever for controlling the machine for total taking operations and for controlling the two means carried by the differentially movable means to select the total counter from the selected pair of counters for operation. 20
33. In a machine capable of accumulating single item transactions and items of different classes of multiple item transactions and taking totals thereof, single counters appropriate to said single item transactions, pairs of counters appropriate to the different classes 25 of multiple item transactions, each pair comprising an item counter and a total counter, a differentially movable means common to all counters for selecting one of the single counters or one of the pairs of counters for operation, manipulative means for controlling the movement of said differentially movable means, means carried by the differentially 30 movable means for causing an operation of the counter selected from the single counters or one counter from the pairs of multiple-item counters during accumulating operations, other means carried by said differentially movable means for causing an operation of the total counter of a selected pair of 35 counters during total taking operations, an add and total control manipulative lever for controlling the machine for accumulating operations and for taking the totals of single item transactions and multiple item transactions, means controlled by said lever for causing operation of the total counter selected, and means also controlled by said lever for preventing an operation of any counter when said lever controls the machine 40 to take totals of single item transactions. 45
34. In a machine of the class described, the combination of a bank of keys, groups of totalizers, and a sliding member movable under control of the keys for selecting a totalizer in each of the groups of totalizers. 50
35. In a machine of the class described, the combination of a bank of keys, a member movable differentially under control of said keys, a plurality of totalizers, and means 55 operated by said member and adapted to select the same totalizer under control of different keys. 60
36. In a machine of the class described, the combination of a bank of keys, a member movable differentially under control of said keys, a plurality of totalizers, and a cam operated by said member and shaped to select the same totalizer under the control of different keys. 65
37. The combination of a bank of keys, a plurality of totalizers, a plurality of counters, and means under the control of different keys for selecting the same totalizer and different counters. 70
38. The combination of a single item transaction keys, a multiple item transaction key, a differentially movable member controlled by said key, a plurality of counters, a plurality of totalizers, and means actuated by said member under control of one of said single item keys and said multiple item keys for selecting the same totalizer and different counters. 75
39. In a machine capable of accumulating single item transactions of variable amounts and variable items of multiple item transactions, means for accumulating a total of both classes of variable transactions, and counting means for counting separately the number of transactions of each class. 80
40. In a machine of the class described, a main operating mechanism, counters, an operating mechanism for said counters adapted to be connected and disconnected from said main operating mechanism, a total operating control lever, and members operated by said lever for disconnecting said counter operating means from said main operating means and for maintaining such disconnection throughout a total operation. 85
41. In a machine of the class described, a main operating mechanism, counters, an operating mechanism for said counters adapted to be connected and disconnected from said main operating mechanism, means for controlling the machine for total read and reset operations, cam means operated by said control means for disconnecting said counter operating means from said main operating means, and other means also operated by said control means for maintaining it disconnected during certain read and reset operations. 90
42. In a machine capable of accumulating and total-taking operations, counters, an operating mechanism for said counters adapted to be connected and disconnected from said main operating mechanism, a total control means, means operated by said control means for disconnecting said counter operating means from said main operating means, and other means also operated by said control means for maintaining said disconnection throughout certain total taking operations, said disconnecting means being non- 95

operative during another total taking operation and accumulating operations.

43. The combination of a plurality of sets of counters, manipulative means; means adjusted under control of the manipulative means for selecting one of said sets of counters, said last mentioned means being provided with a plurality of devices, one of which devices is normally in effective position to control a counter for adding; and other manipulative means to render the normally effective device ineffective and to render the ineffective device effective.

44. The combination of a plurality of sets of counters, a plurality of keys; differentially movable means controlled by the keys for selecting a set of counters, said differentially movable means being provided with a plurality of devices, one of which devices is normally in effective position to control a counter for adding; and a lever to render the normally effective device ineffective and to render the ineffective device effective.

45. In a machine of the class described, an item counter, actuating means therefor, means co-operating with said actuating means to render it effective, and a total control means for causing said co-operating means to move into ineffective position.

46. In a machine of the class described, an item counter, actuating means therefor, sliding means co-operating with said actuating means to render it effective, and a total control means for causing said co-operating means to move into ineffective position.

47. In a machine of the class described, an item counter, actuating means therefor, spring actuated retractable means co-operating with said actuating means to render it effective, and a total control means for causing said co-operative means to move into ineffective position.

48. In a machine of the class described, an item counter operated during accumulating operations, a total counter operated during total operations, an actuating means for each counter, and means common to said actuating means for operating the same.

49. In a machine of the class described, an item counter operated during accumulating operations, a total counter operated during total taking operations, an actuating means for each counter, means common to said actuating means for operating the same, and means for rendering the operating means effective to drive either counter.

50. In a machine of the class described, an item counter, a total counter, common operating means for the counters, manipulative means for controlling the machine for accumulating items and for causing said operating means to actuate said item counter, and means for controlling said machine for total taking operations and for causing said operating means to actuate said total counter.

51. In a machine capable of accumulating single item transactions and multiple item transactions, and of taking their totals, counters for counting the number of separate item transactions, the number of items in multiple item transactions and the number of multiple item transaction total taking operations, and means for operating said counters.

52. In a machine capable of accumulating single item transactions and multiple item transactions, and of taking their totals, counters for counting the number of separate item transactions, the number of items in multiple item transactions and the number of multiple item transaction total taking operations, means for operating said counters, and means for disabling said operating means during operations in which totals of single item transactions are taken.

53. In a machine capable of taking totals of single item and multiple item transactions, counter operating means normally operable in total taking operations, and means for preventing an operation of said operating means during operations in which totals of single item transactions are taken.

54. In a machine capable of taking different classes of totals, counters for certain classes of totals, operating means therefor, and means for preventing an operation of the operating means when totals of transactions other than those of said certain classes are taken and for actuating said operating means when said certain classes of totals are taken.

55. In a machine of the class described, the combination of total taking mechanism, adjustable means adapted in a plurality of positions to control said mechanism for total taking operations, a counter, and counter operating means functioning under control of said adjustable means when in a certain position of adjustment, said counter operating mechanism remaining idle when the adjustable means is in another position of adjustment.

56. In a machine of the class described, adding means, total taking means, a manipulative means movable into positions to control the machine for adding, for the taking of totals of multiple item transactions, and the totals of single item transactions, and counter operating means adapted to be rendered operative by the manipulative means when the manipulative means is in the first two positions and adapted to be rendered inoperative by the manipulative means when the manipulative means is in the last position.

57. In a machine of the class described, a manipulative means movable into positions to control the machine for adding, for the taking of totals of multiple item transactions, and the totals of single item transactions, counter operating means, and a cam movable

under control of said manipulative means for permitting the operating means to function when the manipulative means is in the first two positions and to remain idle when the manipulative means is in the last position.

58. In a machine capable of accumulating items and taking totals thereof comprising a plurality of totalizers, means for counting the number of items accumulated, means for counting the number of times totals are taken, a bank of keys, and means controlled by one of said keys for selecting the same totalizer in item accumulating and total taking operations and the respective appropriate counters in item accumulating and total taking operations.

59. In a machine capable of accumulating items, an item counter; actuating means therefor, a slidably mounted member, a pivoted support for the slidably mounted member to position the slidably mounted member relatively to the item counter, and a cam for controlling the position of the slidably mounted member on the support to render the actuating means effective and ineffective.

60. In a machine of the class described; an item counter; actuating means therefor; a spring actuated retractable and projectable member to determine the effectiveness of the actuating means, said member adapted in its projected position to cooperate with said actuating means to render the actuating means effective; and an element for supporting said member adapted to also move the member into the projected position.

In testimony whereof I affix my signature.
BERNIS M. SHIPLEY.
